UNITED STATES PATENT OFFICE.

WILLIAM H. PERRY, OF CONCORD, NEW HAMPSHIRE.

DESIGN FOR A MONUMENT.

SPECIFICATION forming part of Design No. 21,571, dated May 24, 1892.

Application filed April 28, 1892. Serial No. 431,062. Term of patent 3½ years.

To all whom it may concern:

Be it known that I, WILLIAM H. PERRY, a citizen of the United States, residing at Concord, in the county of Merrimac and State of

5 New Hampshire, have invented and produced a certain new and original Design for Monuments, of which the following is a specification.

Figures and reference-letters will be used 10 on the accompanying drawing to denote the different features of my design.

The base 1 has four vertical sides of nearly equal width, which terminate at their top in an obtuse frustum of a pyramid, as seen at 2. 15 The pedestal is of similar form, proportionately smaller than the said base, and has four vertical sides 3, which terminate at their top in an acute frustum of a pyramid, as at 4, one or more sides of which may be provided with 20 a raised tablet 5. The shaft has four vertical sides 6, which terminate at their top in an obtuse pyramid 7.

Other features of my design consist in the 25 depressed tablets 8, formed one upon each of the vertical sides of the shaft and having the configuration shown.

Still other features of my design are the 30 different character of the surfaces, those lettered A representing rock-work, B hammered work, and C polished work. The tablets 8 are for the most part polished, having a border of hammered work, as shown.

Having described my design, what I claim is—

The design for a monument, substantially 35 as shown and described.

In testimony whereof I affix my signature in presence of two witnesses.

WILLIAM H. PERRY.

Witnesses:

J. B. THURSTON,
CARRIE E. EVANS.
